UNITED STATES PATENT OFFICE.

JONAS NORTHRUP, OF HOPEDALE, MASSACHUSETTS, ASSIGNOR, BY MESNE ASSIGNMENTS, TO DRAPER CORPORATION, OF HOPEDALE, MASSACHUSETTS, A CORPORATION OF MAINE.

LET-OFF MECHANISM FOR LOOMS.

Application filed November 16, 1923. Serial No. 675,123.

The present invention relates to let off mechanism for looms.

The common types of looms provide let-off mechanisms by which the warps are let off from the warp beam at a rate governed by the warp tension. The variations in the rate of let-off are ordinarily regulated by the movements of the whip roll over which the warps pass. In addition it is sometimes desirable to provide means for slackening the warps excessively under abnormal operating conditions of the loom. For example, the copending application of Northrop, Serial No. 647,151, filed June 22, 1923, Patent No. 1,603,708, illustrates an anti-bang by which the whip roll is bodily moved to relieve the tension of the warps in case the shuttle is not boxed on the forward beat of the lay, thereby preventing a smash. The connections between the whip roll and let-off mechanism are such that under these conditions the let-off mechanism is operated to let off an excessive amount of warp threads from the warp beam, thereby leaving a thin place in the cloth upon resumption of operation.

The object of the present invention is to provide a loom having a let-off mechanism which will be rendered inoperative upon excessive movements of the whip roll under abnormal conditions. To this end the invention consists in the mechanism herein-after described and particularly defined in the claims.

In the accompanying drawings illustrating the preferred form of the invention, Fig. 1 is a right hand side elevation of the improved loom under normal operating conditions; Fig. 2 is a similar view showing the relative position of the parts at the time of the operation of the anti-bang; Fig. 3 is a detail rear view showing the mounting for the whip roll; Fig. 4 is a side elevation of the let-off mechanism; Fig. 5 is a top plan view, partly in section, of the let-off mechanism under normal operating conditions when the lay is at back center; and Fig. 6 is a top plan view of the let-off mechanism when it is rendered inoperative.

The illustrative embodiment of the invention comprises a loom having a side frame 10, whip roll 12 and warp beam 14. The whip roll is rotatably mounted in brackets 16 secured to the whip roll shaft 18 which is

journalled in blocks 20 slidingly received in brackets 22. The rock shaft and connected parts are normally retained in rearward position by means of heavy compression springs 24.

The let-off mechanism comprises a worm wheel 26 connecting with the warp beam gear 28 and meshing with a worm 30 secured to a vertical shaft 32 suitably journalled in a bracket 33 secured to the loom frame. The shaft 32 also has secured to it a ratchet wheel 34 which is adapted to be engaged by a let-off pawl 36 mounted upon a pawl arm 38. The arm 38 carries a hub 40 loosely rotatable on the shaft 32 and encircled by a torsion spring 42 which urges the pawl arm in a clockwise direction as viewed from above. The pawl is pressed toward the ratchet by a compression spring 44 taking between the pawl and the pawl arm. The pawl arm is provided at its extremity opposite from the pawl with an upwardly extended pin 46 received within the slot 48 of the head 50 which is mounted on and reciprocated by a rod 52 connected with the lay sword of the loom (not shown). The pawl arm 38 is provided with a depending lug 54 adapted to be engaged by the foot 56 of a pawl stop lever 58 which is connected at its upper end with the whip roll shaft 18 through adjustable toothed cap members 60 and 62, the former being keyed to the rock shaft and the latter forming a part of the lever 58. The lever 58 is normally urged rearwardly to hold the whip roll in an elevated position against the tension of the warps by a compression spring 64 encircling a rod 66 which is connected at one end with the lever 58 and slidingly received in a bracket 68 attached to the frame, the spring taking between the bracket 68 and a collar 70 on the rod. The let-off mechanism thus far described is similar to that disclosed in the patent to Northrop, No. 1,448,081, dated March 13, 1923, to which reference may be had for a more detailed description. Suf-
fice it to say that on the rearward movement of the link 50, corresponding to the rearward beat of the lay, the pawl arm 38, which is now not positively engaged by the link, is free to rotate under the action of the spring 42, thereby drawing the pawl over the ratchet teeth until the lug 54 engages the foot of the pawl stop lever. This posi-

tion of the parts is illustrated in Fig. 5, corresponding to back center position of the lay. On the forward movement of the link 50, corresponding to the forward beat of the lay, the rear end of the slot picks up the stud 46 and moves the pawl arm so as to rotate the ratchet and let off the warp threads from the warp beam. It will be seen that the amount of motion of the ratchet depends upon the position at which the pawl is stopped, which depends in turn upon the position of the pawl stop lever as determined by the pressure of the warp threads upon the whip roll.

15 The illustrated loom is also provided with an anti-bang of the type disclosed in the co-pending application of Northrop above referred to. The loom frog 76, which may be of any usual or preferred construction, is connected by links 78, one on each side of the loom, with the rock shaft 18. The frog is also connected by rods 80 with the pawl stop lever 58 at a point 82 below the upper end of the lever. In case the shuttle is absent from both shuttle boxes on the forward beat of the lay, a dagger 84 on the lay is caused to be depressed in the usual manner to engage the frog and move it forwardly. Owing to the connections between the frog and the rock shaft 18, the whip roll is moved bodily forward from the position illustrated in Fig. 1 to that shown in Fig. 2, thereby slackening the warps so that the lay on its forward beat may push the shuttle against the fell without damage to the warps. Provision is also made for knocking off the loom which occurs ordinarily at approximately front center.

It will be seen that upon operation of the anti-bang and consequent forward movement of the whip roll the pawl stop lever will be moved forwardly a considerable distance, thereby taking the pawl arm out of the positive control of the pawl stop foot 56. If no additional means were provided an excessive amount of warp would be let off, thereby making a thin place in the finished cloth. This excessive let-off may occur either on the beat up of the lay preceding knocking off or upon resumption of operation. The former condition may occur if the pawl stop lever is moved out of engagement with the lug 54 before the stud 46 is engaged by the rear end of the slot 48, thereby permitting the pawl to follow the foot 56 for a number of teeth until the pawl arm is positively engaged by the link 50. After knock off of the loom, the operator ordinarily turns the loom over by hand to back center in order to gain access to the shuttle. In moving the parts toward back center position, the link 50 moves rearwardly, thereby permitting clockwise rotation of the pawl arm under the action of its torsion spring. The pawl stop lever also moves rearwardly

and will engage the lug 54 before the parts have completed their rearward movement, so that upon continued rearward movement of the lever the ratchet is rotated to let off an excess of warp threads.

According to the present invention, there is provided a pawl guard or shield 90 of slightly larger diameter than the ratchet wheel and having a hub 92 loosely rotatable on the shaft 32. The pawl guard normally rests directly above the ratchet wheel and assumes the position shown in Fig. 5 out of engagement with the pawl. The guard is adapted to be moved into the position shown in Fig. 6 to engage an upwardly extended portion 94 on the pawl to move the latter out of engagement with the ratchet when the anti-bang is caused to operate. To this end the guard is provided with a nose 96 normally abutting a part of the loom frame, as shown in Fig. 5. A bell crank lever 100, pivoted on the loom frame at 102, is provided with a cam surface 104 which rests against the under side of the cap member 60 against which it is urged by means of a tension spring 106 connected between one arm of the lever and the loom frame. The lower end of the lever is provided with a lug 108 which normally lies immediately adjacent the nose 96 of the pawl guard. It will be seen that when the frog is moved forwardly, with consequent forward motion of the whip roll shaft 18, the cam surface 104 is depressed, thereby rocking the bell crank about its pivot and causing the pawl guard to rotate one quarter revolution to lift the pawl out of engagement with the ratchet. The extent of movement of the guard is determined by the engagement of a second nose 110 on the guard with a block 112 on the bracket 33. The parts now assume the position shown in Fig. 6. It will be seen that if the loom is now turned over to move the lay to back center the pawl will play over the edge of the pawl guard without engaging the ratchet. Just as the rock shaft 18 is moved into its final rearward position the cam surface 104 is raised, thereby permitting the lever 100 to move to its normal position, the lug 108 striking the nose 110 of the guard and rotates the latter back to its original position, thus permitting normal operation of the loom. It will be seen that the pawl stop lever 58 has substantially completed its rearward movement before the pawl guard is returned to normal position, so that the pawl is positively held by the pawl stop in proper position before it is permitted to engage the ratchet teeth.

While it is preferred to employ the specific construction and arrangement of parts shown and described it will be understood that this construction and arrangement is not essential except so far as specified in the claims and may be changed or modified.

without departing from the broader features of the invention.

The invention having been described, what is claimed is:

- 5 1. A loom having, in combination, a warp beam, a let-off mechanism comprising a ratchet, a pawl, means for oscillating the pawl, means for rotating the warp beam upon rotation of the ratchet, a whip roll, a movement of the whip roll to regulate the 55 action of the let-off mechanism, an anti-bang for sliding the whip roll toward the front of the loom to prevent a smash, means actuated by said sliding movement for rendering the let-off mechanism inoperative, and 60 means for holding the whip roll so that it will not partake of its rocking movement as it is moved frontwardly by the anti-bang.
- 10 2. A loom having, in combination, a warp beam, a whip roll mounted for rocking movement toward and from the warp beam, a let-off mechanism, a bell-crank lever having a short arm that is connected to the whip roll and a long arm that extends downwardly adjacent the let-off mechanism 70 and which is adapted to be shifted by the rocking movement of the bell-crank lever to vary the action of the let-off mechanism, an anti-bang for shifting the whip roll in a direction to slack off the warp to prevent a smash, and means operable by the whip roll independently of said bell-crank lever for rendering the let-off mechanism inoperative 75 upon actuation of the anti-bang.
- 15 3. A loom having, in combination, a warp beam, a let-off mechanism consisting of a ratchet and pawl, and means for oscillating the pawl, connections between the ratchet and the warp beam for rotating the latter to let off the warps, a whip roll, connections 25 between the whip roll and the let-off mechanism for determining the extent of oscillation of the pawl, an anti-bang for moving the whip roll in case the shuttle is absent from both boxes on the forward beat of the 30 lay, a pawl guard shield, and a lever adapted to be moved by the whip roll to move the pawl guard shield into position to hold the pawl out of engagement with the ratchet upon the operation of the anti-bang.
- 35 4. A loom having, in combination, a warp beam, a whip roll mounted for rocking movement toward and from the warp beam and also supported for sliding movement toward the front of the loom, a let-off mechanism, means controlled by the rocking movement of said whip roll in response to variations in the tension of the warp to regulate the action of the let-off mechanism, an anti-bang for sliding the whip roll toward the 40 front of the loom to prevent a smash, and means actuated by said sliding movement for rendering the let-off mechanism inoperative.
- 45 5. A loom having, in combination, a warp beam, a whip roll mounted for rocking movement toward and from the warp beam and also supported for sliding movement toward the front of the loom, a let-off mechanism, means controlled by the rocking 45 movement of the whip roll to regulate the action of the let-off mechanism, an anti-bang for sliding the whip roll toward the front of the loom to prevent a smash, and means actuated by said sliding movement for rendering the let-off mechanism inoperative.
- 50 6. A loom having, in combination, a warp beam, a whip roll mounted for rocking movement in response to variations in the tension of the warp and for sliding movement, a let-off mechanism, means controlled by the rocking movement of the whip roll 55 in response to variations in the tension of the warp to regulate the action of the let-off mechanism, an anti-bang for sliding the whip roll in a direction to slack off the warp and prevent a smash, and means actuated 60 by said sliding movement for rendering the let-off mechanism inoperative.
- 65 7. A loom having in combination, a warp beam, a whip roll mounted for rocking movement and also for sliding movement, a let-off mechanism, means controlled by one 65 of said movements of the whip roll in response to variations in the tension of the warp to regulate the action of the let-off mechanism, an anti-bang for imparting the 70 other of said movements to the whip roll to slack off the warp and prevent a smash, and means actuated by the last mentioned movement of the whip roll for rendering the let-off mechanism inoperative when the anti-bang is actuated.

JONAS NORTHRUP.
